PATENTED JUNE 9, 1908.

H. P. MERRIAM.

OXYGEN CUTTING APPARATUS.

APPLICATION FILED OCT. 30, 1907.

Witnesses:

UNITED STATES PATENT OFFICE.

HENRY P. MERRIAM, OF NEW YORK, N. Y.

OXYGEN-CUTTING APPARATUS.

No. 890,289.

Specification of Letters Patent.

Patented June 9, 1908.

Application filed October 30, 1907. Serial No. 399,971.

To all whom it may concern:

Be it known that I, HENRY P. MERRIAM, a citizen of the United States, and resident of the city, county, and State of New York, 5 have made certain new and useful Inventions Relating to Oxygen-Cutting Apparatus, of which the following is a specification, taken in connection with the accompanying drawing, forming part of the same.

10 This invention relates to oxygen cutting apparatus and relates especially to apparatus in which plates of iron or similar material are simultaneously oxidized and fused by an oxidizing cutting jet and heated to the 15 ignition point by blow-pipe action, using liquid or similar hydrocarbon fuel so as to render the apparatus more readily portable.

In the accompanying drawing showing an 20 illustrative embodiment of this invention and in which the same reference numeral refers to similar parts in the several figures, Figure 1 is a longitudinal sectional view. Fig. 2 is a transverse sectional detail taken substantially along the line 2-2 of Fig. 1. 25 Fig. 3 is a detail of the control valve taken substantially along the line 3-3 of Fig. 1.

Any desired liquid fuel having a sufficiently high heating value may be used in this apparatus, such as kerosene, gasoline or 30 similar petroleum hydrocarbons. This fuel may be admitted under suitable pressure and in regulated quantities to the apparatus by the fuel coupling 46 on the end of the pipe 40. A suitable check valve may be provided in 35 this fuel pipe as the valve 35 normally pressed against its seat by the spring 36 and inclosed within the casing 37. In this way the fuel may be certainly and regularly fed to the vaporizer which may be in the form of the conical coil 3 in which it is vaporized and the fuel 40 vapor superheated, if desired, before delivery through the end of this pipe into the fuel passage 61, see Figs. 1 and 2. From this passage the vaporized fuel may be delivered 45 through the burner nozzle 34 in such quantity as is determined by the threaded burner valve 32 provided with a suitable stuffing box 33 and adjusted by the handle 31. This burner nozzle 34 delivers the superheated 50 and vaporized fuel in a strong jet into the rear of the burner tube 1, drawing in air by injector action, the mixture issuing through the gauze burner tip 2 at the other end of this U-shaped burner tube so as to heat the vaporizer to the desired extent.

A suitable handle for the apparatus may

be constituted by the tubular handle 39 supported by the end flange 38 and at the other end by the valve casing 73. These parts may be secured together in any desired way 60 as by the supports 67 which may be fastened to the flange 38 and engaged by suitable bolts 66 on their outer ends so as to hold the parts firmly together. These supports may, as indicated, engage the burner tube 1 and 65 the head 25 of the apparatus to hold the parts in proper relative position. The casing 73 may be formed with the oxygen connection 47 and with a control valve governing the admission of the oxidizing agent to the 70 heater pipe 13 and the cutter pipe 30, which may be connected with the valve casing by the bushings 41 and 42. The control valve 57 may be of conical form normally pressed home against its seat in the casing by 75 a spring 49 held in position by the cap 74. The controller 43 may be secured upon the valve stem by the screw or bolt 45, so that the valve is readily rotated by this handle to bring the valve ports into proper relation to 80 the apertures in the casing and control the supply of oxygen to the heater and cutter pipes and connected apparatus. For this purpose the valve may have the radial admission port 48 with the wide mouth indicated in Fig. 3, coöperating with the oxygen inlet 56 in the connection 47. In this way, 85 the oxygen is admitted to the axial passage 75 which when the valve and controller are in the cutting position indicated in full lines in 90 Figs. 1 and 3 communicates with the heater outlet 53 and heater pipe by the heater port 54 which preferably has the wide angle mouth indicated. The amount of fluid passing into this heater pipe may be regulated by 95 the heater valve 52 provided with the threaded portion 51 so that by operating the handle 44 the opening between the valve and its seat may be regulated to adjust the amount of oxygen flowing into the heater 100 pipe. The constricted radial cutter port 50 may be formed in the control valve communicating with the axial passage 75 and coöperating with the cutter outlet 55 and cutter pipe when the controller and valve are in the 105 cutting position indicated. When, however, the controller and valve are rotated an eighth of a turn so that the controller assumes the dotted position 243 indicated in Fig. 3, this constricted cutter port 50 will of course be 110 moved out of alignment with the cutter outlet 53 so that no oxygen will be admitted to

the cutter pipe and jet. The admission port and heater port will, however, under these circumstances still be in open connection with the oxygen inlet 56 and the heater outlet 53 so that oxygen will still be supplied to the heater pipe 13. By moving the controller another eighth turn into the dotted position 153, the admission and heater ports will be moved out of alinement with the coöperating apertures in the casing so that the oxygen will be entirely cut off from the apparatus. In this way the heater valve may be adjusted to the desired extent and left in this position while the heating and cutting operations may be instantly controlled by moving the controller as described.

The head 25 secured to the supports 67 may have the tip 21 rigidly but detachably connected therewith by the screw coupling 20 24. The internal nozzle 22 having a replaceable end, if desired, may be mounted within this tip by having a sliding connection in the head 25 and the adjustable asbestos packing 26 at the upper end thereof. By providing 25 the collar 28 with a coöperating adjusting screw 27 engaging a flange or lug on the head 25, the nozzle may be moved longitudinally with respect to the head and tip so as to adjust the annular opening 72 between the 30 two conical portions of these two parts so that heating fluid from the annular passage 63 would issue from this adjustable opening as a conical heating jet of the desired volume and intensity. The cutting jet of oxygen 35 issues from the fine cutter jet 71, the oxygen passing through the cutter pipe 30 and axial passage 23 in the nozzle. A suitable mixer casing 15 may be connected with the head by screwing the threaded end 16 of the mixer 40 into the head, the flange 14 of this mixer engaging the casing and forming a tight union therewith in connection with asbestos or similar interposed packing, if desired. Vaporized and heated fuel from the fuel passage 45 61 may pass through the cross passage 5 in which a suitable strainer 58 may be located before the fuel enters the inclined passage 6 communicating with the annular passage 7 supplying fuel to the threaded fuel valve 11. 50 The strainer 58 may consist of a cylinder formed by rolling a number of thicknesses of fine wire gauze together into open cylindrical form so as to tightly fit the passage 5 while being held in position at the other end by the 55 screw cap 59. In this way the fuel gas is forced to pass through this strainer in which the carbonized material is deposited so that such material is not undesirably deposited in the succeeding portions of the apparatus. 60 A similar strainer 60 may also be held by the cap 62 in position to act on the fuel which issues from the burner nozzle 34. By adjusting the handle 10 on the stem 9 of the fuel valve 11, the amount of vaporized fuel 65 passing through the fuel jet 8 is regulated

and the valve is held tightly in adjusted position by the packing 12 of asbestos or other material. This fuel passes through a suitable shield 20 of wire gauze or other material in the mixer casing and then may pass 70 through suitable radial openings 64 into the mixer passage 17 where it meets the oxygen from the inlet jet 65, the mixed gases passing down through the passage 18, 19, into the annular passage 63 and then issuing from the 75 heater jet in the form of an intensely hot conical jet which maintains the metal at the ignition temperature at the point where the cutter jet of oxygen impinges upon it.

Having described this invention in connection with an illustrative embodiment, to the details of which disclosure the invention is not, of course, to be limited, what is claimed as new and what is desired to be secured by Letters Patent is set forth in the appended 85 claims.

1. In oxygen cutting apparatus, a fuel pipe having a check valve, a connected vaporizer and fuel passage provided with cylindrical gauze strainners through which the 90 vaporized fuel passes, a burner nozzle connecting with said fuel passage through an adjustable burner valve, a burner tube coöperating with said burner nozzle and having an annular air inlet opening around said nozzle 95 and a burner tip within said vaporizer, a head having a tip, an adjustable nozzle mounted therein to form an adjustable conical heater jet, a cutter jet within said heater jet and communicating with an oxygen passage in said nozzle, a mixer having an adjustable fuel valve connected with said fuel passage and a shield and fuel openings leading into a mixing passage with which the oxygen inlet jet communicates, said mixing 100 passage being connected with the heater jet by an annular passage around said nozzle, a handle provided with a valve casing, a control valve and connected controller mounted in said casing, a cutter pipe connected to 110 said nozzle and said casing, a heater pipe connected to said mixer and said casing, an adjustable heater valve mounted in said control valve to control the heating fluid passing therethrough, there being a constricted 115 cutter port in said control valve coöperating with said cutter pipe and wide heater and admission ports in said valve communicating with said heater pipe and an oxygen inlet.

2. In oxygen cutting apparatus, a fuel 120 pipe having a check valve, a connected vaporizer and fuel passage provided with gauze strainners through which the vaporized fuel passes, a burner nozzle connecting with said fuel passage through an adjustable burner 125 valve, a burner tube coöperating with said burner nozzle and having an air inlet adjacent thereto and a burner tip within said vaporizer, a head having a tip, a nozzle mounted therein to form an annular heater 130

jet, a cutter jet within said heater jet and communicating with an oxygen passage in said nozzle, a mixer having an adjustable fuel valve connected with said fuel passage, a handle provided with a casing, a control valve mounted in said casing, a cutter pipe connected to said nozzle and casing, a heater pipe connected to said mixer and casing, an adjustable heater valve mounted in said control valve to control the heating fluid passing therethrough, there being a constricted cutter port in said control valve coöperating with said cutter pipe and wide heater and admission ports in said valve communicating with said heater pipe and an oxygen inlet.

3. In oxygen cutting apparatus, a fuel pipe, a connected vaporizer and fuel passage, a burner nozzle connecting with said fuel passage through an adjustable burner valve,
- 29 a burner tube coöperating with said nozzle and said vaporizer and having an air inlet opening adjacent said nozzle, a head having a tip, an adjustable nozzle mounted therein to form an adjustable annular heater jet, a
- 25 cutter jet within said heater jet, a valve casing, a control valve in said casing, a cutter pipe connected to said nozzle and said casing, a heater pipe connected to said mixer and said casing, an adjustable heater valve mount-
- 30 ed in said control valve to control the heating fluid passing therethrough, there being a constricted cutter port in said control valve coöperating with said cutter pipe and a wide heater port communicating with said heater
- 35 pipe.

4. In oxygen cutting apparatus, a fuel pipe having a check valve, a connected vaporizer and fuel passage provided with gauze strainers through which the vaporized fuel
40 passes, a burner nozzle connecting with said fuel passage through an adjustable burner valve, a burner tube coöperating with said burner nozzle and having an air inlet adjacent thereto and a burner tip within said
45 vaporizer, a head having a tip, a nozzle mounted therein to form an annular heater jet, a cutter jet within said heater jet and communicating with an oxygen passage in said nozzle, a mixer having an adjustable fuel
50 valve connected with said fuel passage, a handle provided with a casing, a control valve mounted in said casing, a cutter pipe connected to said nozzle and casing, a heater pipe connected to said mixer and casing,
55 there being a constricted cutter port in said control valve coöperating with said cutter pipe and wide heater and admission ports in said valve communicating with said heater pipe and an oxygen inlet.

60 5. In oxygen cutting apparatus, a fuel pipe, a connected vaporizer and fuel passage, a burner nozzle connecting with said fuel passage through an adjustable burner valve, a burner tube coöperating with said nozzle
65 and said vaporizer and having an air inlet

opening adjacent said nozzle, a head having a tip, an adjustable nozzle mounted therein to form an adjustable annular heater jet, a cutter jet within said heater jet, a valve casing, a control valve in said casing, a cutter pipe connected to said nozzle and said casing, a heater pipe connected to said mixer and said casing, there being a constricted cutter port in said control valve coöoperating with said cutter pipe and a wide heater port communicating with said heater pipe. 75

6. In oxygen cutting apparatus, a vaporizer and connected fuel passage, a burner nozzle connected with said fuel passage, means to control the fuel passing through 80 said burner nozzle, a burner tube coöperating with said burner nozzle and vaporizer, a head having a heater jet, an oxygen cutter jet, a mixer connected to said fuel passage and said heater jet, a handle provided with a valve 85 casing, a cutter pipe connected to said casing and said head to supply said cutter jet, a heater pipe connected to said casing and supplying oxidizing fluid for said heater jet, and a control valve mounted in said casing 90 and controlling the admission of oxidizing fluid to said cutter and heater pipes.

7. In oxygen cutting apparatus, a vaporizer and fuel passage, a burner tube co-operating with said vaporizer, means to regulably supply said burner tube with fuel from said fuel passage, a head having a heater jet and cutter jet, a mixer connected with said heater jet and means to regulably supply fuel from said fuel passage to said mixer. 100

8. In oxygen-cutting apparatus, a vaporizer, means to heat said vaporizer by fuel produced by said vaporizer, a head having a heater jet and a cutter jet, and means to supply fuel from said vaporizer to said heater jet. 105

9. In oxygen cutting apparatus, a head having a cutter jet and heater jet, a mixer connected to said heater jet and having a fuel supply, a handle and connected valve 110 casing connected to said head, a cutter pipe connected to said casing and head to supply said cutter jet, a heater pipe connected to said casing and mixer, and a control valve in said casing having a constricted cutter port 115 coöperating with said cutter pipe and a wide heater port coöperating with said heater pipe.

10. In oxygen cutting apparatus, a head having a cutter jet and a heater jet, a valve 120 casing and control valve therein, a cutter pipe connected to said casing and said head to supply said cutter jet, a heater pipe connected to said casing and said head to supply 125 said heater jet, said control valve being provided with means to admit fluid to said heater pipe alone or to admit fluid simultaneously to said heater pipe and cutter pipe.

11. In oxygen cutting apparatus, a vaporizer, a burner tube coöoperating with said 130

vaporizer to heat the same, means to supply said burner tube with fuel from said vaporizer, a head having a heater jet and cutter jet, a mixer connected with said heater jet and means to supply fuel from said vaporizer to said mixer.

12. In oxygen-cutting apparatus, a vaporizer, means to heat said vaporizer by fuel

from said vaporizer, a head having an oxidizing cutter jet and a substantially surrounding heater jet and means to supply fuel from said vaporizer to said heater jet. 10
